UNITED STATES PATENT OFFICE.

EDWARD RIPLEY BURGESS, OF BROOKFIELD, MASSACHUSETTS.

TAG-FASTENER.

1,196,514.

Specification of Letters Patent. Patented Aug. 29, 1916.

Application filed January 10, 1916. Serial No. 71,226.

To all whom it may concern:

Be it known that I, EDWARD R. BURGESS, a citizen of the United States, and a resident of Brookfield, in the county of Worcester 5 and State of Massachusetts, have invented a new and Improved Tag-Fastener, of which the following is a full, clear, and exact description.

My invention relates to a fastener more 10 particularly intended for use in fastening a tag to the cord or wrapping material of packages of merchandise, although the device is capable of use in other situations.

A purpose of the invention is to provide a 15 fastener of simple form and which may be produced cheaply, having at the opposite ends thereof members adapted to be quickly and securely engaged in the fastened position.

20 The invention will be particularly explained in the specific description following.

Reference is to be had to the accompanying drawings forming a part of this specification in which similar reference characters 25 indicate corresponding parts in both views.

Figure 1 is a perspective view showing my improved fastener employed in securing a tag to the tie cord of a package; and Fig. 2 is a plan view of the fastener.

30 In forming the fastener embodying my invention, a piece of resilient wire or equivalent material is employed, and made to form an elongated body member 10 ranging along one side of the fastener. At each end the 35 material is return bent substantially parallel with the body member 10 and spaced therefrom, the returned members, designated by the numerals 11 and 12, constituting shanks of separate hook members. The terminals 40 of the shanks are again return bent at the inside of the shanks to produce the bills 13, 14 of the respective hooks.

The bills, 13, 14, of the hooks lie in close juxtaposition to the body member 10 and are 45 spaced from the shanks 11, 12. Also, preferably, the shanks, 11, 12, are of unequal length, this being particularly advantageous in securing a tag C to the tie cord B or the wrapper of a package, since the smaller 50 hook, 12, 14 will suffice for the securing of the tag while the longer hook, 11, 13, may be engaged with facility with the cord B or other article to which the fastener is secured.

The described formation results, as will 55 be seen, in reversely disposed hooks lying at

the same side of the body member 10 and all in a common plane. Either hook member, it will be clear, constitutes a handle for the manipulation of the opposite hook member, each hook presenting a substantial total 60 effective width for the convenient grasping and manipulation of the device.

The oppositely disposed hooks are separated, the intervening space 15 serving for the entrance of the articles to be passed beneath the hooks and after entrance of the articles, for instance, the cord B and tag C, beneath the respective hooks, the spaces, 16, 17, between the bills of the hooks and the shanks thereof will prevent the accidental 65 disconnection of the fastener since the cord B or the tag C will be guided past the end of a bill, 13, 14, into the space 16 or 17, and be thus prevented from gaining entrance between the bill of the hook and the body 70 member 10.

When using the device when fastening the tag to burlap, the end opposite the tag is passed through the burlap and upon partially withdrawing the device, burlap will 80 enter between the body member 10 and the return terminal 13, the same as the cord and thus securely hold the device to the burlap.

Having thus described my invention I 85 claim as new and desire to secure by Letters Patent:

As a new article of manufacture, a tag fastener formed from a piece of resilient material bent upon itself at different distances from its ends to form inwardly extending hook members of unequal length and terminating short of and at different distances from the center of the body of the material, said members lying on the same 90 side of the said body parallel therewith and spaced therefrom, the terminals of the said hook members being bent back upon themselves into engagement with the body, whereby elongated hooks of different lengths 100 and spaced from each other will be formed to permit either hook to serve as a handle for the manipulation of the other hook.

In testimony whereof I have signed my name to this specification in the presence of 105 two subscribing witnesses.

EDWARD RIPLEY BURGESS.
